UNITED STATES PATENT OFFICE.

CAMILLE DE VLEESCHOUWER AND JOHANNES TACOMA, OF AMSTERDAM, NETHERLANDS.

DESK, TABLE, OR CABINET.

1,079,962.

Specification of Letters Patent.

Patented Dec. 2, 1913.

Application filed February 20, 1913. Serial No. 749,601.

To all whom it may concern:

Be it known that we, CAMILLE DE VLEESCHOUWER and JOHANNES TACOMA, subjects of the Queen of the Netherlands, both residing at Amsterdam, Kingdom of the Netherlands, have invented certain new and useful Improvements in or Connected with Desks, Tables, or Cabinets, of which the following is a specification.

- 10 The invention relates to improvements in or connected with desks, tables or cabinets but more particularly to a writing desk, adapted to support a disappearing typewriter or like machine wherein the central 15 part of the top of the desk can be slid and folded in a particular manner into a vertical position beneath said top and a table or board normally situated in a space beneath the top of the desk is arranged to 20 take, at the same time, by means of parallel motion levers the place of said central part of the desk top. A typewriter, calculating machine or the like may thus stand on the table or board in the interior central part 25 of the desk beneath the top thereof ready for use. The motion of the movable central part of the desk top is transmitted by means of levers and links to the table or board while the whole is balanced by springs and 30 counter weights and a very moderate power is therefore sufficient to raise or lower the machine.

The device is particularly suitable for a "Minister" desk.

- 35 A desk or table constructed in the manner referred to always leaves, unlike other known systems of construction where an obliquely arranged board is merely made to fold with the machine attached to it, sufficient space for the knees and legs of the operator sitting in front of the same, and therefore, as regards comfort, is in no way inferior to an ordinary desk, while it is attended with the advantage of always keeping in readiness a typewriter or like machine of the usual size.

In the accompanying drawings which illustrate by way of example a desk, supporting a typewriter, constructed according 50 to the present invention, Figure 1 is a vertical transverse section of the desk taken on the line 1—1 of Fig. 3. Fig. 2 is a similar view to Fig. 1 but with the central part of the desk top slid and folded back and 55 the table or board and typewriter raised

ready for use. Fig. 3 is a front elevation of the desk partly in section and Fig. 4 is a front elevation of the lever and link mechanism separately drawn to an increased scale.

The central part 1 of the top 2 of the desk is connected therewith by means of pivotally mounted arms or links 3 and 4 in such manner that the central part 1, which is approximately of the width necessary to afford space for the knees, is supported on both sides by arms or links 3 and 4. The arms or links 3 and 4 rotate around the short fixed journals or pivots 6 and 7 which project from the inner walls 5 of the desk. The arms 3 are pivotally connected with the central part 1 at or near the front edge thereof by means of the journals 8 while the arms 4 rotate around the journals 9 upon the central part 1 at or near the rear edge thereof. The length of the arms 3 and 4 and the position of the journals 8 and 9 are so calculated that the central part 1 can be slid or swung back from the horizontal position (Fig. 1) into a vertical position (Fig. 2). The horizontal typewriter table 10 is suspended on both sides upon the links or arms 11 and 12 which form a parallel guide. Now in order that the table 10, upon which the typewriter or like machine 13 is placed, may be raised and brought forward, while the central board 1 is folded or pushed back, arms or levers 14 are furnished which are fixed with the arms 4 while bell crank levers 15, capable of rotating about fixed pivots 14 are connected by means of the intermediate links 16 and 17 with the arms 13 and with the links 12.

After the displacement of the central part 1 of the top 2 of the desk, the mechanism assumes the position illustrated in Fig. 2 when the typewriter is raised. The movable parts could easily be balanced by means of counterweights, but it is preferable to employ springs for that purpose. According to this invention, the rods 12 are connected with torsion springs 18 in an appropriate manner as shown in Fig. 4. Small boxes 19 which are connected with the arms 4, pass through the walls 5, while the flanges 20 of said boxes are connected with the springs 18. The pivots 24 of the arms 12 are extended across the side drawers 21 of the desk and are secured to the outer walls 22. The ends of the springs are now rigidly 110

connected with the fixed flanges attached to the extensions of the pivots 24 and by an appropriate choice and arrangement of springs, the whole can be balanced.

5 It is clear that when the typewriter is in its raised position as shown in Fig. 2, pressure upon the table 10 or upon the typewriter cannot bring down the said table because such pressure is transmitted to the 10 front end of the arms 12 and said arms which rotate around the pivots 24, are supported by the intermediate links 17 and the bell crank levers 15 while the pivots 25, 26 and 14 lie in a straight line or at a dead 15 center. Pressure upon the table 10 is therefore without effect and furthermore the weight of the central part 1, which rests in the folded position upon projections 28 offers resistance to said pressure by its own 20 weight. If however, the central part 1 is brought forward and raised by means of the handle 29 the table 10 is lowered together with the machine while the bell crank lever 15 is turned back by the arms 4 and the 25 arms 13 and the intermediate parts 16 of the same, and finally the position of the parts is again as illustrated in Fig. 1. In order to permit the lowering of the several 30 links or arms these are arranged in different vertical planes and, where necessary, bent in such manner that the motions thereof do not interfere with one another (Fig. 4). Now in order that the machine standing upon the table 10 may be protected in 35 the front when the desk is closed (Fig. 1), a wall 31, capable of rotation around the axes 30 is provided between the inner walls 5 of the desk while counterweights 32 tend to keep this wall vertical. Upon the central 40 part 1 being turned over or folded, the wall 31 is tilted forward (Fig. 2) by the front edge of the table 10, while upon the desk being closed again, the wall 31 is made to return to the projection 33 and is then kept 45 in a vertical position by the flange or projection 35 arranged upon the lower edge of the central part 1 and furnished with a groove 34.

What we claim is:

50 1. In a desk, a movable section in the center of the desk top adapted to be swung into a vertical position beneath the same, links by one end pivotally mounted on fixed centers and at the other end pivotally connect- 55 ed to said movable section for supporting and guiding the same, a table for carrying a typewriter or other machine suspended upon links pivotally mounted at one end upon fixed centers beneath the desk top

and at the other end pivotally connected 60 to said table, springs for counterbalancing the weight of the machine upon the table, a bell crank, links coupling one arm of said bell crank with the links of the movable section and the other arm with the links 65 of the table in such manner that when the latter is in its raised position certain of said coupling links will be at dead center and thus support the table, a pivotally mounted frontboard and weights for counterbalancing said frontboard substantially as set forth.

2. In a pedestal desk, a central movable section in the desk top at its front part pivotally supported on links pivotally mounted 75 on the sides of the well or knee space of the desk, near the top thereof and at its rear part pivotally supported on links or levers having cranks or offsets and pivotally mounted on the sides of the well or knee 80 space of the desk at a suitable point between the top and bottom of the desk the parts being so arranged that the movable section is adapted to be swung backward into a vertical position into the body of the desk, a 85 table for carrying a typewriting or other machine suspended in a horizontal position at the front upon links pivotally mounted on the sides of the well or knee space immediately beneath the desk top and slightly to 90 the rear of the pivots of the front links of the movable section and at or near the rear suspended on links curved to avoid the fixed pivots of the links of the movable section, the other ends of the curved links being pivotally mounted on fixed centers carried by the sides of the desk immediately beneath the top thereof, bell cranks turning on fixed centers at the sides of the desk, links connecting one arm of the bell cranks 100 through links with the cranks or offsets of the links or levers of the movable section and the other arms of which bell cranks are pivotally connected to the curved links of the table, the parts being so arranged that 105 when the table is in its raised position certain of said links will be at dead center and thus support the table substantially as set forth.

In testimony whereof we have hereunto 110 set our hands in presence of two subscribing witnesses.

CAMILLE DE VLEESCHOUWER.
JOHANNES TACOMA.
